UNITED STATES PATENT OFFICE.

WALTER H. KELLEM, OF RICHMOND, VIRGINIA, ASSIGNOR TO AMERICAN AUTOMATIC TRAIN CONTROL CORPORATION, OF BALTIMORE, MARYLAND, A CORPORATION OF MARYLAND.

WAYSIDE SIGNAL AND TRAIN-CONTROLLING SYSTEM.

Application filed November 15, 1920. Serial No. 424,159.

To all whom it may concern:

Be it known that WALTER H. KELLEM, a citizen of the United States, residing at Richmond, in the county of Henrico and

5 State of Virginia, has invented certain new and useful Improvements in Wayside Signal and Train-Controlling Systems, of which the following is a specification.

This invention relates to improvements 10 in wayside signal and train controlling systems and has particular reference to an apparatus involving the use of ramp rails on the roadway with track circuits, and devices to connect or disconnect said ramp 15 rails with or from a current supply, as is now well known in the art.

One object of the present invention is to provide an improved train control mechanism in which signal mechanism and ramp 20 rails are employed, whereby the conditions at the signal and the conditions at the ramps for any block or section will positively be alike.

Another object of the invention is to provide an improved system for train control combining a three position signal, ramp rails, a track relay and a line relay all of 25 which are controlled by polarized circuits.

A further object is to provide improved 30 means for controlling the circuit to ramp rails that are located at a braking distance in front, or in advance of a signal that governs the entrance to a block when used in connection with three position automatic 35 signals.

A still further object is to provide simple, improved and efficient means for controlling one or more ramp rails located in front, or in advance of a signal, whereby to transmit 40 to the engineer advanced information as to the condition of the next wayside signal ahead.

Another object is to provide an improved arrangement of circuits in connection with 45 wayside signals and ramp-rails which will not decrease the track capacity; will permit one block overlap for following movement, as now practiced in three-position signal arrangements; which will provide 50 positive protection against rear-end collisions on double-track, which does not interfere with the present signal arrangement and which can be installed at a minimum cost.

With the above and other objects in view, 55 the invention is illustrated in the accompanying drawings, wherein,—

Fig. 1. shows in a diagrammatic way the mechanism and circuits utilized in connection with adjacent track-sections and arranged in accordance with the present invention with the devices and circuits in the normal or clear condition.

Fig. 2. illustrates the mechanism and circuits in the next adjacent track-sections 65 but in the caution position.

Fig. 3. shows the same mechanism in the next sections but with the devices and circuits in the danger or stop position.

Fig. 4. illustrates the normal position of 70 the relay and flow of current.

Fig. 5. shows the reverse position of the relay and current flow, and

Fig. 6. illustrates the neutral or zero position of the relay when all current is cut 75 off.

In carrying out my invention I provide the track rails with insulation 10 at intervals whereby to form a series of blocks and each block is sub-divided by means of 80 insulated joints 11, in the track-rails whereby to form two track-sections 12 and 13 for each of said blocks. (A block in this instance presumably being from signal to signal.)

At the entrance to each section 12 of a block I provide a signal means 14, which latter may be a three position semaphore or a series of three light indication, so that clear, caution and danger indications may 90 be shown at each wayside signal.

Near the exit of the said section 12 of each block I also provide two ramp-rails 15 and 16 respectively,—the ramp 15, being a signal-ramp, while the ramp 16 is what 95 is known as a stop-ramp.

These ramps are so arranged as to be engaged by contact means on the vehicle as the latter travels on the track-rails whereby stop or signal means on the vehicle may be actuated according to whether or not either or both ramps is or are energized or deenergized,—that is, connected with or cut off from a current supply along the track-way.

100 In the present disclosure of my invention I show what is termed a three position A. C. signal device 14, at the entrance to each

block or the entrance to the block-section 12, and in practice this signal device is so connected with motor means as to effect an operation of a plurality of circuit-breakers

5 17—18—19 and 20 respectively whenever the signal is operated, as will presently be more fully described.

Each track-section 12 is provided with a track-relay 21 which has connections 22 and 10 23 with the two track rails near the entrance to the said block and section.

Near the exit of the same track-section 12, there is provided connections 24 and 25, to the low voltage terminals of an auxiliary 15 transformer 26.

This auxiliary transformer 26 also has additional terminals for a purpose that will presently be explained.

20 *Connections and operation of the signal device.*

Each track relay 21 controls a plurality of contact-fingers 27 and 28 which latter, through the operation of the relay 21 are 25 caused to assume one of three positions.

The contact finger 27 operates between two contacts 29 and 30 of which the contact 29 is normally engaged by said finger 27 when the section is clear, while contact 30 30 will be engaged by said finger 27 when the block section in advance is occupied, and when the finger 27 is held out of engagement with both contacts it may be said to be in a zero position at which time the section 35 is occupied.

The contact finger 28 operates between two contacts 31 and 32, of which the contact 31 is normally engaged by said finger 28 when the section is clear; while the contact 40 32 will be engaged by said finger 28 when the block section in advance is occupied, and when finger 28 is held out of engagement with both contacts 31 and 32 it may be said to be in a zero position, at which time the 45 section is occupied.

At this point it is deemed desirable to point out that the circuit breakers 17—18—19 and 20 are all operated by the motor mechanism of the signals so that they will 50 assume 45 degree—90 degree or zero positions, according to the position of the signal itself, as and for a purpose that will presently be more fully explained.

It should be understood that in operation, 55 the track relay 21 is normally energized and when in the normal position, holds the fingers 27 and 28 in engagement with the contacts 29 and 31 respectively;—that when said relay is deenergized by a vehicle short-circuiting the track-connections, said fingers 27 and 28 assume a zero or neutral position, and that when the relay is again energized 60 as the vehicle leaves that section, said fingers 27 and 28 will engage contacts 30 and 32, and finally, through the operation of a

pole-changer or circuit-reverser. The said fingers 27 and 28 are caused to move to the normal position again when the vehicle passes into the second block ahead by means that will now be explained.

As it is one of the objects of this invention to produce like signal conditions at the ramp and wayside signals, certain mechanisms are introduced or interposed between the signal and ramps to effect this result, 75 which mechanism includes a track relay 33, which is provided with a plurality of contact fingers and a line relay 34. Both of these relays are of the same type as relay 21 in that they are three-position relays, but relay 34 is a high-voltage relay while relay 33 is a low-voltage relay which corresponds to A. C. current signalling practice.

The relay 34 is supplied with current from auxiliary transformer 35, at the signal 85 location.

Relay 33 is supplied with current from auxiliary transformer 36, at the signal location.

The ramp rails 15 and 16 are supplied 90 with current from a set of low-voltage terminals on auxiliary transformers 26.

Reference has hereinbefore been made to three-position relays. To make it clear just what this term means I have illustrated in 95 Figs. 4, 5 and 6 of the drawing three diagrams of the track rails 8 and 9 and track relay 21.

These relays have certain characteristics which allow the armature of the relay to 100 assume three positions—namely, normal, reverse and neutral. At normal, current flows through the coils in a left to right direction, which causes the armature to assume the normal position, closing the normal contacts. 105 Reverse position is taken by the same armature when current flows through the coils in a right to left or opposite direction, which closes the reverse contacts. Neutral position is assumed by the armature when there 110 is no current on the coil,—the armature being assisted to this position by a counter-weight and gravity.

Referring to Fig. 2, track relay 33 has been caused to assume normal position by 115 means of the circuit breaker or pole-changers 17 and 18 of signal 14 in Fig. 2 establishing a positive current connection from transformer 35 (Fig. 2) as follows: by wire 38 to circuit breaker 17, thence by 120 wire 38^a to the primary coil of transformer 36, thence to negative side of the primary coil 36, thence by wire 41 to circuit breaker 18, thence by wire 41^a, wire 41^b to negative side of secondary of transformer 35, thus 125 completing the circuit between the secondary of transformer 35 and the primary of transformer 36.

Another circuit is established for relay 33 as follows:—positive current from sec- 130

ondary of transformer 36 Fig. 2, thence by wire 38^b to track rail 8; thence by said track rail 8, section 13, to wire 39 to coil of relay 33 through coil of said relay 33 to wire 40,

5 thence by track rail 9, of track section 13, to wire 41^c, to negative side of secondary of transformer 36, thus completing the circuit.

In order to change the polarity of current supply to track relay 21 of Fig. 1, it is necessary to provide a pole changing arrangement at track relay 33 of Fig. 2, which has the form, in this case, of contact fingers 42 and 43,—the same fingers being a part of said relay 33. This arrangement of contacts performs the same function as the circuit controllers 17 and 18 at the signal 14

15 in that it changes the polarity of current in the wires to the relay according to the position of the contacts.

20 The circuit for this relay 21 is as follows:

Current from main transformer 44, Fig. 2, from secondary positive side flows by wire 45 to contact finger 43 of relay 33, normal, thence by wire 46 to the primary side of auxiliary transformer 26, Fig. 2, thence to negative side of primary of auxiliary transformer 26, thence by wire 47 to contact finger 42, of relay 33, normal, thence by wire 48 to negative side of secondary of main transformer 44, thus completing a circuit between the secondary of transformer 44 and the primary of transformer 26.

The track circuit for relay 21, Fig. 1 is 35 as follows:

Current from secondary positive side of auxiliary transformer 26, Fig. 2, by means of a low voltage tap, by wire 25, to track rail 8, section 12 of Figs. 1 and 2, then by 40 said track rail 8, to a wire 22, then to coil of relay 21, of Fig. 1, through coil of said relay 21, then by wire 23 to track rail 9 of section 12, Figs. 1 and 2, then by said track rail 9 to a wire 24, then to negative 45 side of secondary of auxiliary transformer 26, thus completing the circuit.

It will thus be seen that positive energy flows through the coil of relay 21 (Fig. 1) from a left to right direction which causes 50 the contact fingers 27 and 28 to assume a normal position when the vehicle 37 is in track-section 12 of Fig. 3 which is two blocks ahead, which normal position of relay 21 in Fig. 1 closes the 90 degree control 55 circuit to the signal mechanism 14 and causes the signal in Fig. 1 to go to clear position.

Normal circuit for line relay 34.

60 Current flows from positive side of main transformer 35 by wire 38 to contact finger 27 of relay 21 to contact 29, normal, by wire 51, thence by wire 52 to circuit-breaker 19, normal, thence by wire 53, to coil of relay 34; through coil 34, by wire 54 to contact

55; contacts-finger 56 normal, of relay 33; thence by wire 57 to circuit breaker 20; then by wire 58 to the negative side of transformer 35.

This is the circuit for this relay 34 when 70 the signal 14 is clear and it will be noted that positive current is flowing through the coils in a right to left direction which causes contact fingers 49 and 50 to assume normal position.

The reverse position of this relay 34 is obtained when the signal 14 assumes caution position and the circuit breakers 19 and 20 assume caution position.

The reverse circuit for relay 34 is as follows:

From positive side of transformer 35 by wire 38 to contact finger 27 reverse, to contact 85 30 by wire 59 to circuit breaker 20; by wire 57 to contact finger 56, normal, contact 55; wire 54 to coil of relay 34; through coil and by wire 53 to circuit breaker 19 and by wire 58 to negative side of transformer 35. Thus changing the flow of current from right to left.

Signal ramp rail circuit.

Current flows from positive side of low voltage tap of auxiliary transformer 26 by 95 wire 60 to contact finger 49 of relay 34 normal, then by wire 61 to contact finger 62 of relay 33 normal; by wire 63 to ramp-rail 15; through apparatus on engine to ground on track rail 9; to negative side of transformer 26.

This circuit energizes ramp rail 15 when signal 14 is clear and gives a clear indication on the vehicle.

When signal 14 indicates caution, relay 34 reverses position of contacts 49 and 50 thereby opening the circuit which causes clear indication to be received on the vehicle when the latter passes the ramp rail 15 and closes the caution ramp rail signal circuit.

Caution ramp rail circuit.

Current flows from positive side of low voltage tap of auxiliary transformer 26, by 115 wire 60 to contact finger 50 of relay 34, normal or reverse; wire 64 to contact finger 65 of relay 33 normal, by wire 66 to ramp rail 16; through apparatus on engine to ground on track rail 9, to negative side of transformer 26.

This circuit energizes stop rail 16 when signal 14 indicates either caution or clear condition.

Operation by movement of vehicle from 125 block to block.

When a vehicle passes insulated joints 11 and enters section 13 of Fig. 1, track-relay 33 assumes a neutral position by reason of the short-circuiting of the current there-

through from transformer 36 (Fig. 1). When this happens, current to ramp rails 15 and 16, which guard said section 13 of Fig. 1, is cut off, and both ramps are then 5 dead or deenergized.

The vehicle now moves into section 12 of Fig. 1 and upon passing insulated joints 10, deenergizes track-relay 21 (Fig. 1) and contact fingers 27 and 28 assume a neutral 10 position by reason of current from transformer 26 Fig. 2, being cut off. The signal 14 Fig. 1 will next go to danger position.

Circuit breakers 19 and 20 assume zero 15 or neutral position, which cuts off current supply from transformer 35 Fig. 1, to line relay 34 Fig. 1. The ramp rails for section 13 Fig. 1 remain dead until the signal 14 Fig. 1 changes to caution.

20 Circuit breakers 17 and 18 will have moved to a zero position and thereby changed polarity of current to relay 33 Fig. 1, from transformer 36, so that at that time the condition of the mechanism of Fig. 1 will 25 become changed and be precisely like such mechanism as is illustrated in Fig. 3. The two ramp rails in Fig. 1 therefore remain dead.

The vehicle next passes ramp rails 15 and 30 16 of the next section Fig. 2, which rails are energized so that a current can be picked up by contacts on the vehicle to keep the vehicle-mechanism energized while passing those ramps.

35 Next the vehicle passes insulated joints 11 and enters track section 13 of Fig. 2, whereupon, track-relay 33 of Fig. 2, becomes deenergized and assumes a neutral position by cutting off the current thereto.

40 When relay 33 of Fig. 2 is deenergized ramp rails 15 and 16 of Fig. 2 will also become deenergized.

At this moment, signal 14 of Fig. 1 is still at danger and the ramps 15 and 16 of Fig. 45 1 are also still dead.

When the vehicle passes into section 12 of Fig. 2, the track relay 21 of said Fig. 2, becomes deenergized and contact fingers 27 and 28 assume a neutral position because 50 current has been cut off from transformer 26 of Fig. 3 to said relay 21 of Fig. 2.

The circuit breakers 19-20 assume zero or neutral positions which cut off current supply from transformer 35 of Fig. 2 to line 55 relay 34 of said Fig. 2.

The ramp rails 15 and 16 for section 13 Fig. 2 remain dead until signal 14 Fig. 2 changes to caution position.

Circuit breakers 17 and 18 of Fig. 2 will 60 have moved to a zero or neutral position and will have changed polarity of current to relay 33 Fig. 2.

When this change of polarity of current in Fig. 2 takes place, contact fingers 42 and 65 43 Fig. 2, are caused to assume reverse po-

sition to that shown in said Fig. 2. This causes a change in the polarity of current flowing from main transformer 44 Fig. 2 to auxiliary transformer 26 Fig. 2, thence to the low voltage secondary of said latter 70 transformer which change of polarity causes track relay 21 of Fig. 1 to take a position reverse to that actually shown in said Fig. 1. This reversal of the contact fingers 27 and 28 Fig. 1 closes the 45 degree control 75 circuit to the signal 14 Fig. 1, through wires 59 and 32^a which moves the signal to caution position, and this movement causes an operation of the circuit breakers 17-18-19 and 20 of Fig. 1 and they in turn assume a 80 caution position.

When these circuit breakers 17-18-19 and 20 of Fig. 1 assume the caution position, contact fingers 49 and 50 of relay 34 Fig. 1 will assume a position reverse to that 85 shown in said Fig. 1 and relay 33 Fig. 1 will resume normal position by reason of change of polarity by circuit breakers 17-18 Fig. 1, and these changes will close a path for current to the stop ramp rail 16 Fig. 1 90 which now energizes said rail.

Signal ramp rail 15 Fig. 1 is still dead or deenergized, and any vehicle passing over this rail will still receive a caution signal 95 which indicates the position of signal 14 at Fig. 1.

The vehicle now passes into section 13 of Fig. 3 which deenergizes track relay 33 of said Fig. 3 and cuts off current from ramp rails 15 and 16 of Fig. 3 as has been described in connection with the ramps in Fig. 1 and Fig. 2.

Now the vehicle 37 moves to the position shown in Fig. 3 and upon passing insulated joints 10 deenergizes relay 21 Fig. 3; puts 105 signal 14 at danger and circuit breakers 17-18-19 and 20 at zero or neutral position. The circuit breakers 19 and 20 Fig. 3 cut off current supply from transformer 35 Fig. 3 to relay 34 Fig. 3, causing contact fingers 49 and 50 to assume a neutral 110 position.

Circuit breakers 17 and 18 change polarity of current supply from transformer 35 Fig. 3 to auxiliary transformer 36 which change 115 of polarity causes relay 33 Fig. 3 to assume the position shown in Fig. 3. This reversal of current through relay 33 moves contact fingers 42 and 43 so as to change the polarity of current flowing from main transformer 44, Fig. 3 to auxiliary transformer 26, Fig. 3 thence to the low voltage secondary of said latter transformer, which change of polarity causes track relay 21 of Fig. 2 to take the position shown in Fig. 2.

This reversal of the contact fingers 27 and 28 Fig. 2 closes the 45 degree control circuit to the signal 14 Fig. 2, which moves said signal to caution position and this movement causes an operation of the cir- 120 125 130

cuit breakers 17—18—19 and 20 of Fig. 2 and they in turn assume a caution position.

When these circuit breakers of Fig. 2 assume the caution position, contact fingers 49 and 50 of relay 34 of Fig. 2 will assume the reverse position (which is the position shown in Fig. 2) and relay 33 Fig. 2 will resume normal position, as shown in Fig. 2 and these changes will close a path for current to the stop ramp rail 16, Fig. 2 which now energizes said rail.

The normal position of contact fingers 42 and 43 of relay 33 Fig. 2, allows current to flow to relay 21 Fig. 1 from main transformer 44 then to auxiliary transformer 26 thence to low voltage taps in a normal direction which causes contact fingers 27 and 28 Fig. 1 to assume normal position. This normal position of contact fingers 27 and 28 of relay 21 Fig. 1, closes a 90 degree circuit to the motor mechanism of the signal 14 Fig. 1 which causes that signal and its circuit breakers 17—18—19 and 20 to assume a clear position.

Contacts 49 and 50 of relay 34 Fig. 1, assume normal position by reason of the circuit breakers 19 and 20 being moved to the clear position. This reversal of contacts 49 and 50 from reverse to normal, restores current to caution ramp rail 15 Fig. 1 and any vehicle now passing these ramp rails 15 and 16 Fig. 1 will receive a clear indication.

35 *Signal devices and circuits.*

While I have not deemed it necessary to illustrate the signal mechanism in detail, it is to be understood that when a signal is at clear or 90 degree position, a circuit to the motor mechanism of the signal will be closed between finger 27 and contact 29 and finger 28 and contact 31; that when the signal is in the 45 degree or caution position, a circuit to the motor mechanism of the signal is closed between finger 27 and contact 30 and finger 28 and contact 32, and when the signal is in the zero or stop position the fingers are in the normal position and no circuit is completed to the motor mechanism of the signal.

Clear or 90 degree signal circuit.

Current from positive secondary of transformer 35, Fig. 1, flows by wire 38 to contact finger 27 of relay 21, which normally engages contact 29, thence from contact 29 by wire 51 to the motor of the signal 14, then through the motor to operate the latter, then by wire 41 to the negative side of secondary of transformer 35 thus completing the motor circuit for signal 14 and causing the signal to assume a clear position.

Caution or 45 degree signal circuit.

65 Current from positive secondary side of

transformer 35, Fig. 2, flows by wire 38 to contact finger 28 of relay 21, which is reversed in Fig. 2, then through contact 32 and wire 32^a to the motor of the signal 14 to operate said motor; thence by wire 70 41 to negative of secondary of transformer 35 thus completing the caution circuit for signal 14 and causing the signal to assume a caution position.

Stop or zero position of signal.

75

When relay 21, Fig. 3 assumes a neutral position, current will be interrupted through both of the wires 51 and 32^a because both contact fingers 27 and 28 are in a zero position, therefore the counter-weighted semaphore arm drops to danger position by gravity.

Having described my invention, I claim,—

1. In a wayside signal and train-controlling system the combination with a trackway divided into track-sections each of which is electrically insulated from the others, of means for supplying a current to each of said sections; signal and stop ramp rails adjacent to the tracks of one section; a wayside signal device capable of giving three indications such as clear, caution and stop; a plurality of three-position relays and contacts therefor,—one of said relays being connected to each section and means for reversing the flow of current through the relays upon operation of the wayside signal device whereby the indication at a signal will be duplicated at the ramps preceding the same.

2. In a wayside signal and train controlling system, the combination with a trackway divided into track-sections each of which is electrically insulated from the others, of means for supplying a current to each of said sections; signal and stop ramp rails adjacent to the tracks of one section; a wayside signal device capable of giving three indications such as clear, caution and stop; a three position relay for each wayside signal device; circuit reversers actuated by the said wayside signal; connections between the said relay and the track-rails of a section and a three-position track relay to control current to the ramp-rails said latter track-relay being controlled through the circuit-reverser of the wayside signal device.

3. In a wayside signal and train controlling system, the combination with a trackway formed into insulated track-sections, of a signal ramp-rail; a stop ramp-rail; a wayside signal device in advance of said signal and stop ramp rails said signal device being capable of giving clear, caution and stop indications; circuit reversing means operated by said wayside signal; a three-position track-relay adjacent to each wayside signal; another three-position track-

120

125

130

relay for controlling the passage of current to the ramp rails next behind the wayside signal; a current supply for said latter relay and connections between said current supply and said latter track-relay which connections include the circuit reverser devices of the wayside signal.

4. In a wayside signal and train controlling system, the combination with a trackway formed into insulated track-sections, of three position wayside signals at intervals along the trackway; signal and stop ramp rails also at intervals along the trackway to be engaged by contacts on a vehicle before the latter reaches a wayside signal; a three-position track relay adjacent to and controlling each wayside signal; another three-position relay in advance of each ramp-rail location said latter relay being operated by current controlled through the operation of the wayside signal, and a current supply for the ramps which cur-

rent is controlled by said latter three-position relay.

5. In a wayside signal and train controlling system, the combination with a trackway formed into insulated track-sections, of three position wayside signals at intervals along the trackway; signal and stop ramp rails also at intervals along the trackway to be engaged by contacts on a vehicle before the latter reaches a wayside signal; a track relay adjacent to and controlling each wayside signal; a track-relay in advance of the ramp rail locations; a line relay interposed between the two track relays and controlled through circuit breakers of the wayside signal and a current supply for the ramps which current is controlled through contacts of one track relay and contacts of the line relay.

In testimony whereof I affix my signature.

WALTER H. KELLEM.
